UNITED STATES PATENT OFFICE.

THOMAS A. PROCTOR, OF MINGO JUNCTION, OHIO.

CURTAIN-STRETCHER.

1,366,835.

Specification of Letters Patent. Patented Jan. 25, 1921.

Application filed January 8, 1920. Serial No. 350,065.

To all whom it may concern:

Be it known that I, THOMAS A. PROCTOR, a citizen of the United States, residing at Mingo Junction, in the county of Jefferson 5 and State of Ohio, have invented certain new and useful Improvements in Curtain-Stretchers, of which the following is a specification.

This invention relates to improvements in 10 frames for stretching curtains.

The principal objects of the invention are: to provide a frame for stretching curtains which may be adjusted to effectively and evenly stretch curtains of various sizes; 15 to provide improved means for holding a curtain on the frame; and to provide means for holding the securing means in position for engaging a curtain and to conceal or guard the same when the curtain is disposed on 20 the frame.

For the purpose of illustrating the invention, there is shown in the accompanying drawings one form thereof which is at present preferred, since the same has been found 25 in practice to give satisfactory and reliable results, although it is to be understood that the various instrumentalities of which the present invention consists can be variously arranged and organized and that the invention 30 is not limited to the precise arrangement and organization of these instrumentalities as herein shown and described.

The preferred embodiment of the invention is illustrated in the accompanying 35 drawings in which:

Figure 1 is a top plan view of the frame in position for receiving a curtain.

Fig. 2 is a side or edge view of the frame.

Fig. 3 is a detail side view of one of the side rails of the frame, showing to advantage one of the curtain securing rollers, having the pins concealed or guarded in the slots provided in the side rails and secured in 45 position by the locking members.

Fig. 4 is an edge or side view of Fig. 3.

Fig. 5 is a view on the line 5—5 of Fig. 3.

Fig. 6 is a view on the line 6—6 of Fig. 1, and

Fig. 7 is a detail view of the connection 50 between the side rails and end rails of the frame broken away to show the manner of disposing and utilizing the securing bolts therefor.

55 Similar characters of reference indicate

like or similar parts throughout the several views of the drawings, in which:

The curtain frame is shown (see Fig. 1) as formed in two sections A and B hingedly connected together as at 1 and provided 60 with side rails 2 and end rails 3. Secured adjacent the ends of the side rails 2 and on the outer edges thereof are bracket members 4 through two of which extend bolts 5 carried by the end rails 3 and provided with 65 wing nuts 6 for an obvious purpose (see Fig. 7). Each of the end rails 3 is provided with a bracket 7 similar to bracket 4 and through which extend bolts 8 (similar to bolts 5) which engage within the two 70 remaining brackets 4 of the side rails 2 to form an easily adjustable frame for receiving curtains of various sizes and for stretching the same. Upon the central portion of 75 the frame is a transverse adjustable bracing beam 8^a having brackets 8^b for receiving bolts whereby to adjust the same in a similar manner to the adjustment of the side and end rails.

The inner edges of the side rails 2 and 80 end rails 3 are beveled as at 9 and are provided with uniformly spaced apart angular slots 10 and a plurality of similar slots 11 of greater width than the slots 10 for receiving the terminal securing portions 12 85 of collars 13 which engage about reduced cylindrical portions 14 of the cylindrical side and end curtain securing rollers 15 and 16 respectively, which are adapted for limited rotary and longitudinal movement; 90 the latter of which movements is limited by abutment of the shoulders 17 of the reduced portions 14 with the collars 13; and the former of which movements is limited by engagement of uniformly spaced apart 95 longitudinally aligned pins 18 carried on the rollers in a manner clearly illustrated on the drawings.

In order to maintain the rollers 15 and 16 in a position with the pins 18 extending 100 upwardly or disengaged from the slots 10 to engage the edges of a curtain, pins 19 are provided in the reduced portions 14 which upon moving the rollers longitudinally engage in slots 20 in the collars 13 to securely hold the same in an upright position.

Upon engaging the edges of a curtain with the pins 18 the rollers 15 and 16 are moved to disengage the pins 19 from the slots 20 and are rotated until the pins 18 are con- 110

sealed in the slots 10 whereupon the spring catches 21 which are pivoted to the inner edges of the side and end rails are disposed above certain of the pins 18 and are held in place by lugs 22 (see Figs. 3 and 4).

From the foregoing it is thought that the operation of the frame will be apparent, but it is pointed out that the present frame may be quickly knocked down for storing or 10 shipping and when set up will securely, evenly and effectively stretch curtains (even though constructed of fine fabric) of various sizes.

From the foregoing description taken in 15 connection with the accompanying drawings, it is thought that a clear and comprehensive understanding of the construction, operation, and advantages of the invention may be had, but while I have shown 20 and described the device as embodying a specific structure, I desire it to be understood that such changes may be made in said structure as do not depart from the spirit and scope of the invention as claimed.

25 What I claim is:

1. A curtain frame comprising side and end rails, longitudinally slotted brackets arranged on said rails with their slots par-

allel with said rails, means extending through the slots in the brackets for adjusting the rails relative to each other, rollers on the side and end rails capable of longitudinal movement, pins on the rollers for engaging a curtain, and means on the side rails and on said rollers for interlocking engagement to hold said pins in position to receive a curtain.

2. A curtain frame comprising relatively adjustable side and end rails having recesses in one face opening through their inner edges, bearing brackets extending laterally inward from said rails, rotatable pin carrying rods mounted in said brackets and slideable longitudinally therein a predetermined distance, coöperating means carried by said rods and brackets to lock the rods against turning when moved longitudinally in one direction, and means for locking them when moved longitudinally in the other direction, the pins on said rods being housed in said recesses when the rods are locked in the last mentioned position.

In testimony whereof, I affix my signature hereto.

THOMAS A. PROCTOR.
